ATTORNEY.S

UNITED STATES PATENT OFFICE.

MATTHEW J. DOLPHIN, OF BROOKLYN, NEW YORK.

INK-FEEDER.

SPECIFICATION forming part of Letters Patent No. 517,036, dated March 27, 1894.

Application filed May 23, 1891. Serial No. 393,860. (No model.)

To all whom it may concern:

Be it known that I, MATTHEW J. DOLPHIN, of Brooklyn, in the county of Kings, in the State of New York, have invented new and 5 useful Improvements in Ink-Feeders, of which the following, taken in connection with the accompanying drawings, is a full, clear, and exact description.

My invention relates to an improved ink 10 feeder, and has for its object the production of a simple, strong, durable and efficient device which effects an even flow of the ink, and a positive regulation of the flow; and to this end it consists, essentially, in a suitable 15 shell having an ink containing chamber provided with a pocket on its interior, a feeding opening or openings extending from the interior of the pocket to the outer surface of the chamber, and a partially revoluble ad- 20 juster for opening and closing said openings.

The invention furthermore consists in an 25 adjusting rod having one extremity tapered, and seated in the pocket, in the chamber and the other provided with a hand-engaging por- 30 tion, passages extending through the adjuster, and a spring mounted on the adjuster for forcing it into its normal position.

The invention still furthermore consists in the detail construction and arrangement of 35 the parts, all as hereinafter more particu- larly described and pointed out in the claims.

In describing this invention, reference is had to the accompanying drawings, forming a part of the specification, in which, like letters indicate corresponding parts in all the 40 views.

Figures 1 and 2 represent, respectively, side elevation and longitudinal vertical sectional views of my improved invention. Fig. 3 is a 45 top plan view of the parts as illustrated in Figs. 1 and 2. Fig. 4 is a similar view to Fig. 3, the clamp for holding the cap of the inker cylinder in position being removed for the purpose of illustrating the ink inlet opening.

Fig. 5 is a top plan view of the detached cylinder. Fig. 6 is an inverted plan view of the 50 cap for the cylinder. Fig. 7 is a sectional view, taken on line $x-x$, Fig. 2. Fig. 8 is an elevation of the detached lower extremity of the adjuster; and Fig. 9 represents a modified form of pocket.

This invention relates to the same class of

inkers set forth in my previous Patents Nos. 449,110 and 449,405, issued March 31, 1891, and has for its object the production of an 55 inker which is simpler in construction and more convenient and effective in operation than those embodied in said patents.

—A— represents the shell of the inker provided with a chamber —a— and consisting, 60 preferably, of a section of a tube closed at its lower extremity by a head —B— having an upwardly extending post —C—, the lower end of the post being hollow for the reception of a spindle, not illustrated, upon which the 65 inker is supported in its revolution occasioned by suitable mechanism not illustrated.

—D— represents a removable cap for the shell —A— consisting of a round disk having an annular vertical shoulder —d— adapted 70 to enter the upper extremity of the chamber —a— and an annular horizontal shoulder —d'— adapted to rest upon the top edge of the shoulder.

As best seen at Fig. 5, the upper edge of 75 the shell —A— is formed with recesses or downwardly extending grooves —a— for receiving lugs —d'— projecting from the cap —D—. At the center of the cap —D— is the ink inlet opening —D'— which is closed by 80 a shoulder —e— formed upon the outer extremity of a clamp or thumb-screw —E— provided with a screw-threaded lower extremity —e'— adapted to enter a screw-threaded socket —c— in the post —C— for retaining 85 the cap in position and also permitting entrance of ink when the clamp is removed.

—F— represents a pocket provided within the shell —A— at one side of the lower extremity of the post —C— and consisting, 90 preferably, of a tube having a tapering central chamber —f—.

—G— are feeding openings extending from the interior of this pocket —F— to the outside of the shell —A— for permitting out- 95 let or feeding of the ink.

—H— represents an adjuster partially revoluble for opening and closing the feeding passages —G— and permitting or restraining the flow of the ink. As preferably constructed, 100 this adjuster consists of a rod having its lower extremity tapered and tightly seated within the tapered chamber —f— of the pocket —F— and its upper extremity pro-

vided with a hand-engaging portion —*h*— projecting to the outside of the shell —*A*— and consisting, preferably, of a thumb-nut firmly secured to a shank formed upon the 5 adjuster rod. As previously stated the shell —*A*— is revolved by any suitable mechanism, as a frictionally engaging and positively driven roller, for feeding the ink by centrifugal force, and such is the tendency of the ink 10 to feed from the roller that the adjuster must fit the pocket very closely and its adjustment be positive, minute and convenient, since the slightest variation causes the marker to vary the character of its impression. Accordingly, 15 to produce the desired adjustment, the lower extremity of the adjuster, as best seen at Figs. 2 and 8, is formed with passages —*H'*— adapted to register with the openings —*G*— and govern the feed of the ink by the degree 20 of registration with said passages —*G*—.

It will readily be perceived that as the rod —*H*— is partially rotated, the passages —*H'*— are moved into or out of registration with the openings —*G*— and in order to enable 25 the operator to determine readily and positively the degree of adjustment required, the hand-engaging portion —*h*— is provided with a finger —*h'*— movable over an index —*h²*— best seen at Fig. 4. For rendering this 30 adjustment more perfect, minute and certain, the extremities of the openings —*H'*— are formed with tapering slots or grooves —*H²*— which gradually decrease in area, as best seen at Fig. 8.

35 It is evident that in order to obtain a practical adjustment of the adjuster, its lower extremity must tightly fit the chamber —*f*— of the pocket —*F*— and that it must also turn comparatively easy. To attain this result, the 40 chamber —*f*— and the lower extremity of the adjuster —*H*— are made tapering and interposed between the shoulder —*H³*— on said adjuster and the adjacent face of the cap —*D*— is a spring —*I*— which constantly forces 45 said adjuster into its normal position.

At Fig. 9 I have shown, in cross section, a 50 form of pocket which is only partially tubular, but it will be understood that this is no departure from my invention, since the lower extremity of the adjuster is suitably supported at —*h³*— in the shell —*A*—, the inner wall of the tubular pocket may be dispensed with, provided the adjacent faces of the adjuster and remaining portion of pocket bear 55 very closely against each other. I do not, however, regard this as the preferable construction, since even though it requires less material, it requires more careful workmanship.

60 The operation of my invention will be readily perceived from the foregoing description and upon reference to the drawings, and it is evident that the device is very simple, the supply of ink readily replenished by the removal of the clamp —*E*—, and the flow of ink 65 positively regulated by the adjustment of the adjuster or movable rod —*H*—.

It is evident that the parts of my inker may be somewhat changed from those shown and described, hence I do not limit myself to the 70 precise form and construction of the detail parts.

Having thus fully described my invention, what I claim as new, and desire to secure by Letters Patent, is—

1. In an ink feeder, the combination of a shell inclosing a chamber for containing the ink, and provided with a pocket within the chamber having an inlet opening and an opening extending from the interior of the pocket 80 to the outside of the shell for permitting outlet of the ink, and an adjuster arranged within the chamber and movable in said pocket for opening and closing said opening, substantially as and for the purpose set forth. 85

2. In an ink feeder, the combination of a shell inclosing a chamber for containing the ink, and provided with a pocket within the chamber having an inlet opening and an opening 90 extending from the interior of the pocket to the outside of the shell for permitting outlet of the ink, a rod rocking or partially revolute in proximity to said outlet opening for opening and closing the same, and provided with a perforation therethrough, substantially as and for the purpose specified. 95

3. In an ink feeder, the combination of a shell inclosing a chamber for containing the ink, and provided with a pocket within the chamber having an inlet opening and an opening 100 extending from the interior of the pocket to the outside of the shell for permitting outlet of the ink, a movable rod for opening and closing said outlet opening having one extremity arranged within the chamber, a bearing within the chamber for said rod, and a spring for forcing said rod into its normal position, substantially as and for the purpose set forth. 105

4. In an ink feeder, the combination of a shell inclosing a chamber for containing the ink, and provided with a pocket within the chamber having an inlet opening and an opening 110 extending from the interior of the pocket to the outside of the shell for permitting outlet of the ink, an adjuster movable in said pocket for opening and closing said opening, and a spring mounted on the upper extremity of said rod, substantially as and for the purpose specified. 115

5. In an ink feeder, the combination of a shell inclosing a chamber for containing the ink, and provided with a pocket within the chamber having an inlet opening and an outlet opening extending from the interior of the 120 pocket to the outside of the shell for permitting outlet of the ink, and an adjuster movable in said pocket and provided with an opening therethrough having a groove at one extremity of a constantly decreasing area, substantially as and for the purpose set forth. 125

6. In an ink feeder, the combination of a shell inclosing a chamber for containing the ink, and provided with a pocket within the

- chamber having an inlet opening and an outlet opening extending from the interior of the pocket to the outside of the shell for permitting outlet of the ink, a partially revoluble 5 adjuster movable in said pocket and provided with an opening therethrough having a tapering groove at one extremity, and a spring for forcing said adjuster to its normal position, substantially as and for the purpose specified.
- 10 7. In an ink feeder, the combination of a shell inclosing a chamber for containing the ink, and provided with a pocket within the chamber having a tapering interior cavity and having an inlet opening and an outlet 15 opening extending from the interior of the pocket to the outside of the shell for permitting outlet of the ink, and an adjuster having a tapering extremity movable in said pocket, substantially as and for the purpose set forth.
- 20 8. In an ink feeder, the combination of a shell inclosing a chamber for containing the ink, and provided with a pocket within the chamber having a tapering interior cavity, and having an inlet opening and an outlet 25 opening extending from the interior of the pocket to the outside of the shell for permitting outlet of the ink, a rocking or partially revoluble rod having one extremity tapering and movable within the central cavity of the 30 pocket and the other extremity projecting out of the chamber and a hand-engaging portion on said projecting extremity of the rod, substantially as and for the purpose specified.
9. In an ink feeder, the combination of a shell 35 inclosing a chamber for containing the ink, and provided with a pocket within the chamber having a tapering interior cavity, and having an inlet opening and an outlet opening extending from the interior of the 40 cavity to the outside of the shell for permitting outlet of the ink, a rocking or partially revoluble rod having one extremity tapering and seated in the central cavity of the pocket and the other extremity projecting beyond 45 the chamber, a spring encircling the upper end of the rod, and a hand-engaging portion on the upper extremity of said rod, substantially as and for the purpose set forth.
10. In an ink feeder, the combination of a shell inclosing a chamber for containing the 50 ink, and having a cap and an outlet opening in its side wall for the discharge of the ink, an upwardly projecting post within the chamber, a clamp having one extremity engaged with the projecting post and the other bearing against said cap for retaining the cap in position, and an adjuster for regulating the flow through said outlet opening of the shell, substantially as and for the purpose specified.
11. In a feeder, the combination of a shell 60 inclosing a chamber for containing the ink, and having a cap provided with a central opening in its side wall for the discharge of the ink, an upwardly extending post within the chamber provided with a screw-threaded 65 socket, and a screw having a shoulder bearing against the cap for closing the opening, and a screw-threaded shank engaged with the socket in the post, substantially as and for the purpose set forth.
12. In an inker, the combination of a shell 70 inclosing a chamber and provided with a cap having an inlet opening said shell being provided with a pocket within the chamber having a tapering interior cavity and having an 75 inlet opening and an outlet opening from the interior of the cavity to the outside of the shell for permitting outlet of the ink, a partially revoluble rod having one end arranged within the pocket for regulating the flow 80 through said outlet opening and having its other end projecting outside of the chamber and provided with a hand-engaging portion, a lengthwise post within the chamber, and a clamp having one extremity adapted to close 85 the inlet opening of the cap and the other engaged with said post, substantially as and for the purpose specified.

In testimony whereof I have hereunto signed my name, in the presence of two attesting witnesses, at Syracuse, in the county of Onondaga, in the State of New York, this 20th 90 20th day of May, 1891.

MATTHEW J. DOLPHIN.
